DAVID SILBERMAN, OF NEW YORK, N. Y., ASSIGNOR TO SIMON L. RUSKIN, TRUSTEE,
OF NEW YORK, N. Y.

STITCHLESS HOOK TAPE

Application filed February 23, 1927. Serial No. 170,244.

My invention relates to stitchless, rivetless hook or eye tapes in which the hooks or eyes are inserted into the tape fabric without sewing or riveting and in which the pull 5 or strain comes against a fold in the fabric to give strength to the structure, in which the bases of the hooks or eyes are covered, concealed and protected and in which the various plies or folds of the tape are 10 cured together by the wire forming the hooks or eyes without sewing or riveting as has heretofore been customary. The invention is particularly applicable to standard hooks or eyes but special forms may be used 15 without departing from my invention.

There are two kinds of hook or eye tapes in use at the present time. First the type in which the bases of the hooks or eyes are riveted to the tape. This method of production requires wire bending machines to 20 make the hooks or eyes, a machine to form the rivets and a machine to assemble the hooks or eyes, rivets and tape. The hooks or eyes and rivets are generally plated after 25 they are made and a woven fabric tape with a selvage edge is generally used. In the second, or sewed type, the hooks or eyes are formed in wire bending machines and plated and a sewing machine provided with 30 feeding and folding attachments sews them to a strip of fabric. The wire bending machines now in use have an output of about 400 hooks or eyes a minute.

In producing hook or eye tape embodying my improvement the separate assembling machine, the plating plant, the rivet making machine and the special sewing machine are eliminated and strips of piece 40 goods can be used as the tape. The hooks or eyes are formed of plated wire in the wire bending machine and immediately assembled and attached to the tape in practically one operation and at a production output 45 of 300 a minute as compared with a production output of 100 a minute for riveted tape and 75 a minute for sewed hook or eye tape, making the cost of production of my improved hook or eye tape very low in comparison as well as greatly increasing the out-

put with a given number of machines and employees.

In the drawing I have shown my invention applied to a hook tape but I do not limit myself to the precise form shown. 55 Fig. 1 is a face view of a hook tape embodying my invention; Fig. 2 a back view of the structure of Fig. 1; Fig. 3 a sectional view of the structure of Fig. 1 on the line 3—3 thereof; Fig. 4 a sectional view of the tape 60 ready for the insertion of a partially formed hook; Fig. 5 a view of a partially formed hook; and Fig. 6 a sectional view of the structure of Fig. 1 on the line 6—6 thereof. The figures are all exaggerated for clearness 65 of illustration.

In making the hook tape shown a strip of fabric is folded as indicated in Fig. 4 with the return ply 1, the face ply 2, the intermediate ply 3 and the bottom ply 4. 70 At this stage the plies 1 and 4 lie between the plies 2 and 3. The shanks 10 of the partially formed hooks *h* are then pushed through all the plies on the line *a*—*a* of Fig. 4 and the bases 11 are formed below the ply 3. The plies 3 and 4 are then folded back as shown in Figs. 3 and 6 so that the base loops of the hooks will lie between the fold 3—3' (Fig. 6) and be thereby concealed. 75 The shank 10 of the hook passes through the plies 3' and 4, then is exposed on the back, as shown in Fig. 2, and the wire finally passes through the plies 1 and 2 locking all the plies together without the use of sewing or riveting. The bases of the hooks lie 80 against the fold between the plies 3—3' so that great strength is obtained under tension, when in use. As shown in Fig. 6 the edges of the tape overlie one another at the middle portion of the folded tape with the plies 3—3' interposed between them. The operative portions of the hooks or eyes are located at a distance from the edges of the folded tape as shown in Figs. 1 and 6.

As my tape has no lines of sewing it lies 85 flat and straight and can be more easily handled by the operators in sewing it to a garment and as the hook tape is always sewed to a garment face down the exposed wires on the back, as shown in Fig. 2 serve 100

as a guide for the operator in sewing the tape to a garment.

The eye tape embodying my invention is the subject matter of a separate application for patent and my invention resides essentially in folding a piece of fabric to form a multi-ply tape with the wire forming the hooks or eyes passing through the plies to lock them into position so that all sewing or riveting is eliminated.

10 I claim:—

15 1. Stitchless hook tape comprising a strip of fabric folded to form a face ply, a return ply on the back of the face ply, a third ply extending over the free edge of the return play then outwardly to form a fourth ply and inwardly again to form a fifth ply and a hook member passing through all of said plies with its bill exposed on the face 20 ply and its base loops lying in the fold between the third and fourth plies.

25 2. Stitchless hook tape comprising a strip of fabric folded to form a face ply, a return ply on the back of the face ply, a third ply extending over the free edge of the return play then outwardly to form a fourth ply and inwardly again to form a fifth ply and a hook member passing through all of said plies with its bill exposed on the face 30 ply and the base loops lying between the third and fourth plies, the shank of the hook being exposed on the back of the tape.

35 3. Stitchless hook or eye tape comprising a strip of woven fabric folded on itself into a plurality of plies the tape edges overlying the middle portion of the folded tape, fasteners of the hook and eye type passing through said plies and edge portions with their operative portions exposed on the face 40 of the folded tape at a distance from the edges thereof and their bases lying within said folds, the fasteners themselves serving to unite the various plies of fabric.

45 In testimony whereof I have affixed my signature.

DAVID SILBERMAN.
